HENRY P. KRAFT, OF RIDGEWOOD, NEW JERSEY; EDGAR J. PHILLIPS AND EARL A. DARR EXECUTORS OF SAID HENRY P. KRAFT, DECEASED.

DUST CAP.

Application filed October 14, 1918, Serial No. 258,077. Renewed May 20, 1925.

This invention relates to dust caps for tire valves, and aims to provide certain improvements therein.

As customarily made, dust caps are drawn from a sheet metal blank by a succession of cupping operations which gradually deepen the blank into proper form. This process requires repeated annealing which also adds to its expense, and the total time required to complete the cap. Furthermore, this method of constructing the cap is more applicable to easily drawn metal, such as brass. When applied to iron or steel, for instance, greater difficulties are encountered due to excessive wear on the tools, etc.

According to the present invention, I aim to provide a dust cap in which these various disadvantages will be obviated. To this end I construct a cap which is formed of a flat sheet metal blank preferably without drawing operations, or if such operations are employed, I limit them to those which are easily effected. In practising the invention according to the preferred form, I take a flat blank and stamp it into suitable shape, and then roll it or form it into cylindrical shape, and close the end thereof by bending the metal of the end of the cylinder. The invention includes certain other improvements which will be hereinafter more fully described.

In the drawings, wherein I have illustrated several forms of the invention,—

Figure 1 is a plan of a sheet metal blank adapted for the construction of one form of cap.

Fig. 2 is a top edge view thereof.

Fig. 3 is a side view of a partially closed blank.

Fig. 4 is a top view of Fig. 3.

Fig. 5 is an elevation of the completed cap.

Fig. 6 is a top view of Fig. 5.

Fig. 7 is a blank adapted for a modified form of cap.

Fig. 8 is a side elevation of the cap completed.

Fig. 9 is a section on the line 9—9 in Fig. 8.

Fig. 10 is a sectional view of Fig. 9 on an enlarged scale.

Fig. 11 is a sectional view on a similar scale of a modification of Fig. 10.

Referring first to Figs. 1 to 6, let A indi-

cate a suitable blank of sheet metal such as 55 sheet brass, iron or steel. By the use of a proper punch this is formed preferably in one operation from a flat piece of metal. As shown in Fig. 1, the top of the blank is provided with a number of pointed projections B. These may be four in number, as shown, or a less or greater number, if desired. At one side of the blank is formed a series of dove-tailed recesses C, and on the other side a series of similarly shaped projections D.

In constructing the cap, I first prefer to bend the metal into U-shape, as best illustrated in Figs. 3 and 4, it being preferable to leave one of the lugs E of the U-shaped body longer than the other F, as shown in Fig. 4. The cap is then preferably placed upon a cylindrical mandrel and the two edges E and F rolled down, the edge F being rolled slightly in advance of the edge E, 70 so that the projections D may enter the recesses C laterally. If it is desired that the cap shall be screw-threaded at its bottom, it may then be rolled or spun, as shown at G, to reduce its diameter at its foot. The projections B are then bent down toward each other until the end of the cap is closed as best seen in Fig. 6. The precise character of these projections depends upon the shape which is to be given to the closed end of the 85 cap. Where four projections are used, and the end of the cap is to be dome-shaped, the curved and pointed shape indicated in Fig. 1 is best employed. The restricted portion G may then be tapped as shown at H. 90

The construction thus described produces a cap in which the edges are interlocked so as to prevent lateral separation. If desired, the interlocked edges may be given a considerable amount of pressure so as to expand them laterally somewhat to increase the security of the grip upon each other. The cap may be finished in any suitable way, such as by nickel-plating it or the like.

In the modification illustrated in Figs. 7 to 10 a blank J is best employed which is similar to the blank A of Fig. 1, with the exception that the interlocking projections are omitted. This blank is then rolled to cylindrical form and its end closed as in the preceding figures. In some cases the cap will resist lateral separation sufficiently to render it unnecessary to provide any

other means to hold the edges together. I prefer, however, to provide a means for this purpose, and in the drawing I have shown one of such means. By reference to Figure 10, it will be seen that the formation of a reduced portion or neck K which is adapted to receive the screw-thread is usually accompanied by the formation of an external groove. In Figs. 9 and 10 I have shown a means for providing against lateral separation comprising a collar or sleeve L set in such groove and preferably of such thickness as to be substantially flush with the exterior of the cap. This collar is preferably applied by a ferruling machine which reduces its body uniformly without corrugating it, so that the collar presents a smooth and finished exterior. It is preferable to apply the collar before the tapping operation. In the construction of Figs. 1 to 10 the cap is formed with a bottom flange M or M'. In Fig. 11 the flange is formed upon the collar L', and the metal of the cap is spun or turned over slightly at the bottom to confine the collar L' in place.

The edges of the cap may be united in any suitable manner, if desired, in addition to or in lieu of the sleeve.

The claimed invention may receive other

embodiments than those herein specifically 30 illustrated and described.

What I claim is:—

1. A dust cap comprising a structure formed of a flat sheet-metal blank bent into cylindrical form with its longitudinal edges in abutting relation, and having a closed top integrally formed from said blank, and an encircling member surrounding the cap for preventing separation of the abutting edges thereof. 40

2. A dust cap comprising a sheet metal body bent to cylindrical form, having an open end, an endless annulus around said cylindrical body adjacent its open end, and an out-turned flange at said open end, said annulus and outturned flange strengthening said body and providing a broad bearing-face for said end of the body. 45

3. A sheet metal dust cap comprising a body portion having a longitudinal joint 50 and a reduced open end adapted to fit over a tire valve, and an annulus engaging over said reduced end and lying substantially flush with the exterior surface of the cap to reinforce said joint at said open end. 55

In witness whereof, I have hereunto signed my name.

HENRY P. KRAFT.
